LOOPER-ACTUATING AND RETRACTING MECHANISM FOR SEWING MACHINES

Andrew B. Clayton, Union, N. J., assignor to The Singer Manufacturing Company, Elizabeth, N. J., a corporation of New Jersey

Application February 20, 1940, Serial No. 319,827

10 Claims. (Cl. 112—200)

This invention relates to looper-mechanisms for chain-stitch sewing machines and has as an object to provide an improved and simplified looper-mechanism which has a minimum of connections; in which the actuating elements are relatively short, light and compact; which is devoid of all harsh motions and which therefore is better adapted for high-speed operation than are prior constructions.

Another object of the invention is to provide an improved and simplified means for disconnecting the looper-carrier from its actuating mechanism so that the looper may be retracted from its normal operating position to facilitate threading of the looper, and for positively locking the looper-carrier in its operative position when it has been returned thereto.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 is a front elevation of a two-thread chain-stitch sewing machine embodying the present invention, the cloth-plate, presser-foot, and portions of the feeding mechanism being omitted.

Fig. 2 is a plan view of the lower left end portion of Fig. 1, showing, more particularly the improved looper-mechanism.

Fig. 3 is a vertical sectional view substantially on the line 3—3 of Fig. 2.

Fig. 4 is a vertical sectional view substantially on the line 4—4 of Fig. 2 showing, in full lines, the looper and its carrier in their operative positions and in dotted lines in their retracted positions to facilitate threading of the looper.

Fig. 5 is a detail longitudinal sectional view substantially on the line 5—5 of Fig. 2 showing the means, later to be described, for locking the looper-carrier in its operative position.

Fig. 6 is a fragmentary sectional view showing the looper-carrier locking means withdrawn and the looper-carrier swung to inoperative position.

Referring more specifically to the drawings, the invention is disclosed as embodied in a sewing machine having a frame comprising a base 1, standard 2, bracket-arm 3 and bracket-arm head 4. Within the head 4 is reciprocably jour-

naled a needle-bar 5 carrying, at its lower end, an eye-pointed needle 6 which forms one element of a conventional stitch-forming mechanism. The needle-bar is reciprocated in its bearings by the swinging movements of a needle-bar actuating lever 7 fulcrumed at 8 in the arm 3 and actuated by a pitman 9 connected to a crank 10 on a main-shaft driven from a belt-wheel 11.

For convenience in manufacture and assembly, the main-shaft is preferably made in two sections, of which one, designated as 12, is journaled in bearings 13 at the base of the standard, and the other, designated as 14, is journaled in bearings 15 and 16 formed in bearing-blocks 15^a and 16^a supported by the base 1. The shaft-sections 12 and 14 are connected together by a coupling member 17 carrying set-screws 18 and 19 engaging, respectively, the adjacent ends of the shaft-sections 12 and 14.

Intermediate the bearings 15 and 16 the shaft-section 14 carries a looper-actuating crank 20, a feed-lift eccentric 21, and counterweights 22 and 23. These elements are of greater diameter than the diameter of the bearings 15 and 16 for the shaft-section 14. Therefore, so that the shaft-section may be inserted into its bearings, the bearing-block 16^a is made separate from the base 1 and is removably secured thereto by a screw 24, as shown in Fig. 1. Outside of the bearing-block 16^a the shaft-section 14 has secured thereto, as by set-screws 25, a collar 26 which carries an adjustable feed-drive eccentric 27. A conventional four-motioned work-feeding mechanism designated generally as f is actuated from the feed-lift and feed-drive eccentrics 21 and 27, respectively.

Secured upon brackets 28 and 29, which are formed integral with and project upwardly from the base 1, is a throat-plate 30 which supports the work adjacent the stitching point and beneath which is operated the looper, later to be described.

Cooperating with the needle 6 is a chain-stitch looper 31 formed with a thread-eye 32 adapted to carry a looper-thread which, during operation of the machine, is concatenated with the needle-thread to form two-thread chain-stitches. The looper is given endwise movements, transversely of the shaft 14, and sidewise movements substantially parallel to the axis of the shaft 14 to cause proper concatenation of the needle and looper-threads, all as is common to two-thread chain-stitch sewing machines. The looper 31 has its shank 31^a fixed in a looper-

carrier 33, pivoted upon a shoulder-screw 34 carried by an arm 35 which projects rearwardly from a split collar 36 secured by clamp-screws 36^a upon a looper-actuating shaft 37. This looper-shaft is journaled for oscillation and translation in bearings 38 and 39 provided by the base 1.

Oscillatory motion is transmitted to the looper-shaft and to the looper carried thereby, from the crank 20 formed on the main-shaft section 14. This crank is surrounded by a two-part strap 41 (see Fig. 3) having upstanding ears 42 to which is pivotally connected, by a pivot-bolt 43, the upper ends 44 of a pitman 45. The lower end of the pitman is connected by a ball-and-socket joint 46 with the free end of an arm 47 having a hub 48 secured on the looper-shaft 37 by set-screws 49.

Reciprocatory motion is transmitted to the looper-shaft 37, thereby to give to the looper its sidewise movements, in timed relation with its endwise movements, by an eccentric 50 carried by a collar 51 secured upon the shaft-section 14. A pitman 52 has, at one end, a strap 52^a which surrounds the eccentric 50 and is connected, at its opposite end, by a ball and socket joint 52^b with one end of a rock-arm 53, the opposite end of which is clamped upon the upper end of a stub-shaft 54 journaled in an inclined bearing 55 supported by the base 1. At its lower end the shaft 54 carries an arm 56 having, at its free end, a ball 57 fitted between the two halves of a split block 58 which, in turn, is fitted between flanges 59 and 60 secured upon the looper-shaft 37. The arm 53, shaft 54 and arm 56 form, in effect, a bell-crank lever for connecting the pitman 52 with the looper-shaft 37. The flange 59 forms a part of the hub 48 of the looper-oscillating arm 47, hereinbefore mentioned, while the flange 60 is carried by a collar 61 secured upon the looper-shaft 37 by set-screws 62. Thus rotation of the eccentric 50 will, through the elements 52, 53, 54, 56, 57, 58, 59, 60 and 37 transmit sidewise motion to the looper-carrier and the looper 31 carried thereby.

It will be observed that the means for giving sidewise movements to the looper is exceedingly compact and simple in construction having minimum of joints in which lost motion may develop. Also due to the inclined arrangement of the shaft 54, the arm 56 is relatively short and therefore may be made rigid without being unduly heavy. Likewise this construction affords convenient means for permitting lateral adjustment of the looper-carrier and the looper carried thereby without affecting the looper-actuating mechanism, such adjustment being effected merely by releasing the set-screws 49 and 62, shifting the looper-shaft axially, and then retightening the set-screws.

In its normal operating position the looper 31, with its thread-eye 32, is located directly beneath the throat-plate 30. In this position the looper-thread may be passed through the thread-eye 32, to thread the looper, only with great difficulty. To facilitate threading of the looper, this invention provides a simplified means for retracting the looper from its operative position so that the thread-eye 32 will be removed from beneath the throat-plate 30 as shown in dotted lines in Fig. 4. To that end, the looper-carrier 33 is formed with an arcuate slot 63 (Fig. 4) through which the looper-shaft 37 extends. When in its operative position the looper-carrier is in the position shown in full lines in Fig. 4,

with the lower end wall 63^a of the slot 63 in contact with the shaft 37 (see also Fig. 5). The looper-carrier is maintained in that position by the contact of the rounded end 64^a of an adjustable screw 64, threaded into the looper-carrier 33 and projecting through a radial aperture 37^b in the looper-shaft, with the conical end 65^a of a spring-pressed plunger 65 slidably fitted within a bore 37^a formed in the looper-shaft 37. This construction definitely locates and positively holds the looper in its operative position. The screw 64 may be secured in its adjusted position by a jam nut 64'. The plunger 65 is normally held in the position shown in Fig. 5 by a coil-spring 66 surrounding a reduced portion 65^b of the plunger 65 and interposed between the head of the plunger and a plug 67 threaded into the end of the looper-shaft. At its outer end the plunger 65 has secured thereto a nut 68 which may serve as a hand-grasp to permit withdrawal of the plunger in opposition to the spring 66.

When it is desired to retract the looper to the dotted line position shown in Fig. 4 for the purpose of threading the looper, the operator grasps the nut 68 and pulls it outwardly thereby withdrawing the conical end 65^a of the plunger 65 from beneath the end of the screw 64. Then by grasping the looper or its carrier or some part attached thereto, for example, the looper thread-guide 69, the operator tips the looper-carrier forwardly until the upper end wall 63^b of the arcuate slot 63 engages the looper-shaft 37 as shown in Fig. 6. The hand-grasp 68 may then be released and the end of the plunger 65 will thereafter abut against the side of the screw until the looper-carrier is returned to its operative position when the plunger will be shifted forwardly by the spring 66 to lock the looper-carrier as shown in Fig. 5.

From the foregoing it will be perceived that this invention has provided an improved and simplified looper-actuating mechanism including a novel and convenient means of retracting the looper to facilitate threading thereof.

Having thus set forth the nature of the invention what I claim herein is:

1. A looper-actuating mechanism for a sewing machine having a base, comprising a rotary main-shaft, a looper-shaft rotatably and translatable journaled substantially parallel to said main-shaft at one side of a vertical plane passing longitudinally through the axis of said main-shaft; a looper carried by said looper-shaft; a crank on said main-shaft; means, including a universal joint, connecting said crank with said looper-shaft to transmit oscillatory motions thereto from rotary motions of said main-shaft; an eccentric on said main-shaft; a stub-shaft journaled in said base at the opposite side of said vertical plane with its axis inclined away from said main-shaft; an arm secured to said stub-shaft and extending substantially lengthwise of said main-shaft; a pitman connecting said eccentric with the free end of said arm to transmit oscillatory motions to said stub-shaft; and a second arm connecting the other end of said stub-shaft with said looper-shaft thereby to transmit axial motions thereto from the oscillatory motions of said stub-shaft.
2. A looper-actuating mechanism for a sewing machine having a base, comprising a rotary main-shaft; a looper-shaft rotatably and translatable journaled substantially parallel to said main-shaft at one side of a vertical plane passing longitudinally through the axis of said main-shaft;

a looper carried by said looper-shaft; a crank on said main-shaft; means, including a universal joint, connecting said crank with said looper-shaft to transmit oscillatory motions thereto from rotary motions of said main-shaft; an eccentric on said main-shaft; a bell-crank lever fulcrumed on said base at the opposite side of said vertical plane with its axis inclined away from said main-shaft; and a pitman connecting said eccentric with one arm of said bell-crank lever to transmit oscillatory motions thereto, the other arm of said bell-crank lever extending upwardly and forwardly beneath said main-shaft and being connected with said looper-shaft thereby to transmit axial motions thereto from the rotary motions of said main-shaft.

3. A looper-actuating mechanism for a sewing machine having a base, comprising a rotary main-shaft; a looper-shaft rotatably and translatable journaled substantially parallel to said main-shaft at one side of a vertical plane passing longitudinally through the axis of said main-shaft; a looper carried by said looper-shaft; a crank on said main-shaft; means, including a universal joint, connecting said crank with said looper-shaft to transmit oscillatory motions thereto from rotary motions of said main-shaft; an eccentric on said main-shaft; a bell-crank lever fulcrumed on said base at the opposite side of said vertical plane with its axis inclined relative to said plane; spaced flanges carried by said looper-shaft; a pitman connecting said eccentric with one arm of said bell-crank lever to transmit oscillatory motions to the lever from rotary motions of said eccentric, the other arm of said bell-crank lever extending upwardly and forwardly beneath said main-shaft toward the looper-shaft and having a ball on the free end thereof; and a block mounted on said ball and fitted between said spaced flanges on said looper-shaft, said pitman and bell-crank lever thereby transmitting axial motion to the looper-shaft from the rotary motion of said eccentric.

4. A looper-actuating mechanism for sewing machines comprising an oscillatory looper-shaft provided with an axial bore and a radial aperture; a member secured to said shaft; a looper-carrier pivotally mounted on said member at one side of said shaft; an element carried by said looper-carrier and adapted to be projected through said radial aperture into said bore; and means within the bore in said looper-shaft and engaging said element to hold said looper-carrier in a predetermined operative position.

5. A looper-actuating mechanism for sewing machines comprising an oscillatory and axially movable looper-shaft provided with an axial bore and a radial aperture; a member secured to said shaft; a looper-carrier pivotally mounted on said member at one side of said shaft and having an opening surrounding said shaft; an element carried by said looper-carrier and adapted to be projected through said radial aperture; and an axially movable member within the bore in said looper-shaft radially engaging said element to hold said looper-carrier in a predetermined operative position with one end wall of said opening in contact with said looper-shaft.

6. A looper-actuating mechanism for sewing machines comprising an oscillatory and axially movable looper-shaft provided with an axial bore and a radial aperture; a member secured to said shaft; a looper-carrier pivotally mounted on said member at one side of said shaft; an element

carried by said looper-carrier and adapted to be projected through said radial aperture; a spring-pressed plunger within the bore in said looper-shaft and engaging said element to shift said looper-carrier in a predetermined direction; and a stop to limit the movement of said looper-carrier under the influence of said plunger.

7. A looper-actuating mechanism for sewing machines comprising an oscillatory and axially movable looper-shaft provided with an axial bore and a radial aperture; a member secured to said shaft; a looper-carrier pivotally mounted on said member at one side of said shaft; an element carried by said looper-carrier and adapted to have one end thereof projected through said radial aperture into said bore; a spring-pressed plunger located within the bore in said looper-shaft and having a tapered head engaging the end of said element to hold said looper-carrier in a predetermined operative position.

8. A looper-actuating mechanism for sewing machines comprising an oscillatory and axially movable looper-shaft provided with an axial bore and a radial aperture; an arm secured to said shaft; a looper-carrier pivotally mounted on said arm at one side of said shaft and having an opening through which said looper-shaft extends; an adjustable element carried by said looper-carrier and adapted to be projected through said radial aperture; a spring-pressed plunger located within the bore in said looper-shaft and having a conical head radially engaging said element to hold said looper-carrier in a predetermined operative position with one end wall of said opening in contact with said looper-shaft; and means to withdraw said plunger out of contact with said element thereby to permit swinging of said looper-carrier about its pivot to retract the looper-carrier from its operative position.

9. A looper-actuating mechanism for sewing machines comprising an oscillatory and axially movable looper-shaft provided with an axial bore and a radial aperture; a member secured to said shaft; a looper-carrier pivotally mounted on said member at one side of said shaft; a looper secured to said looper-carrier; an element carried by said looper-carrier and adapted to be projected through said radial aperture; and a spring-pressed plunger having one portion within the bore in said looper-shaft and engaging said element to hold said looper-carrier in a predetermined operative position, and another portion projecting out of said shaft; and provided with a hand-grasp by means of which the plunger may be manually retracted out of contact with said element thereby to permit the looper-carrier to be swung about its pivot to an inoperative position to facilitate threading of said looper.

10. A looper-actuating mechanism for sewing machines comprising an oscillating looper-shaft provided with an axial bore; a looper and a looper-carrier supported from said shaft and swingable relative thereto; a member carried by said looper-carrier; an element slidably mounted in said bore and adapted, in one position to engage said member thereby to hold said looper-carrier in its operative position and prevent swinging movement thereof; and means to withdraw said element out of engagement with said member thereby to permit said looper-carrier and looper to be swung to an inoperative position to facilitate threading of the looper.

ANDREW B. CLAYTON.
